UNITED STATES PATENT OFFICE.

KATHERINE LIVINGSTON KELLOGG, OF NEW YORK, N. Y.

DESIGN FOR A TOY CAT.

Application filed January 23, 1926. Serial No. 16,236. Term of patent 7 years.

To all whom it may concern:

Be it known that I, KATHERINE L. KELLOGG, a citizen of the United States of America, and a resident of the city of New York, borough of Manhattan, in the county and State of New York, have invented a new, original, and ornamental Design for Toy Cat, of which the following is a specification.

Reference is to be had to the accompanying drawing in which—

Figure 1 is a front view of a toy cat showing my new design, and

Fig. 2 is a side view thereof.

The design is not a conventional cat, but an idealized design, wherein the face, breast and paws of the animal, the paws being somewhat enlarged or exaggerated, are framed within a border of contrasting color. This contrasting color it will be noticed from Figs. 1 and 2, is best seen in the front view.

I claim—

The ornamental design for a toy cat as shown and described.

KATHERINE LIVINGSTON KELLOGG.
